(57) **CLAIM**

The ornamental design for a refrigerating apparatus, as shown and described.

DESCRIPTION

FIG. 1 is a perspective view of a refrigerating apparatus showing the new design;

FIG. 2 is a back view thereof;

FIG. 3 is a back bottom view thereof;

FIG. 4 is a left view thereof;

FIG. 5 is a right side view thereof;

FIG. 6 is a top view thereof; and,

FIG. 7 is a bottom view thereof.

All broken lines in the figure drawings show unclaimed subject matter and form no part of the claimed design.
